UNITED STATES PATENT OFFICE.

JOHN B. FLINT, OF BOSTON, MASSACHUSETTS.

ARBOR-PRESS.

1,128,240.

Specification of Letters Patent.

Patented Feb. 9, 1915.

Application filed January 2, 1914. Serial No. 809,883.

To all whom it may concern:

Be it known that I, JOHN B. FLINT, a citizen of the United States, residing at Boston, in the county of Suffolk and State 5 of Massachusetts, have invented new and useful Improvements in Arbor-Presses, of which the following is a specification.

This invention relates to improvements in arbor presses and has for its object to provide a simple and easily operated arbor press which will be capable of receiving and positioning a large variety of arbors, as to different diameters thereof, and a large variety of sizes and shapes of pieces into which 10 the arbors are to be forced. In order to position this large variety of arbors and pieces of work into which they are to be forced, or from which they are to be removed, I employ a plate upon which the 15 work directly rests and this plate, which may be termed a "supplementary" work-plate or support rests upon a stationary work-support having a notch therein.

The supplementary work-support is provided with a V-shaped slot extending thereinto from the front edge thereof so that a large variety of diameters of arbors may be accommodated by said V-shaped slot while the pieces into which these arbors are forced, 20 or from which they are to be forced are securely supported and rest upon the supplementary work-support in which said V-shaped slot is provided. In addition to the supplementary work-support being provided with a V-shaped slot, this work-support has its efficiency greatly augmented by 25 being transversely movable upon the stationary work-support of the arbor press—that is, the supplementary work-support can 30 be moved forward and back or sidewise or at any angle so as to bring the V-shaped slot at any desired position relatively to the plunger of the press, and by this combination of the supplementary work-support with 35 the V-shaped slot and by the capability of moving this supplementary work-support to any desired position relatively to the plunger of the press I obtain a press capable of 40 taking practically all sizes of arbors, from 45 large to small, within the extreme capacity 50 of the arbor press employed.

The supplementary work-support hereinbefore referred to is so attached to the press that the same may be quickly positioned and 55 still at the same time its movement may be limited, and furthermore the same is so at-

tached to the press that while the supplementary work-support is universally slideable upon the bed of the press it is not detachable therefrom and will always be found 60 in convenient position to be adjusted relatively to the plunger of the press to receive the work.

In addition to the V-shaped slot in the front of the supplementary work-support, I 65 also provide a series of holes of different diameters which are to be used in cases where it is desirable to support the work into which the arbor is to be pressed or from which it is to be removed close to said arbor 70 and entirely therearound, and these holes are preferably arranged in such a manner that they may be quickly positioned relatively to the plunger of the press, this positioning being obtained by sliding the supplementary work-support forwardly or 75 backwardly, as the case may be, beneath the plunger, the operator being assisted in this positioning operation by the specific construction hereinafter clearly set forth in this 80 specification.

The invention consists in the combination and arrangement of parts set forth in the following specification and particularly pointed out in the claims thereof.

Referring to the drawings: Figure 1 is a side elevation, partly in section, of an arbor press embodying my invention. Fig. 2 is a sectional plan taken on line 2—2 of Fig. 1, with the supplementary work-support or plate shown in two positions, one of said positions being illustrated by dotted lines.

Like numerals refer to like parts throughout the several views of the drawings.

In the drawings, 4 is the frame of an arbor press, the same being provided with a work-support 5 notched at 6 to receive the ends of arbors which are to be forced through work placed on said work-support. 100 A plunger 7, of the usual type, is reciprocatorily arranged in a bearing 8 in said frame 4 and adapted to be reciprocated by a pinion 9 engaging teeth 10 on said plunger and a hand lever 11 connected with said pinion to rotate the same.

The plunger 7 is arranged to be reciprocated at right angles to the surface of the work-support 5 for the purpose of forcing arbors or mandrels from or into the work. 110 A supplementary work-support or plate 12 is mounted on and movable transversely of

said work-support 5, said plate being preferably formed of two layers of material 13 and 14, the lower layer 14 being preferably formed of material such as cast iron, while the upper layer 13 is formed of relatively harder material, such as steel, and is preferably hardened to prevent chipping or wear caused by contact with the work into which the arbors are forced, said layer 13 being secured to the portion 14 by screws 15.

10 The layer 13 is formed in two parts for convenience in manufacture and is preferably joined along the line 16. The plate 12 has a V-shaped slot 17 extending therethrough from top to bottom and opening at the front edge 18 of said plate and is adapted to be adjusted to fit various sizes of mandrels alining with the plunger 7, said V-shaped slot being employed when it is desired to force a mandrel or arbor from a piece of work which is of such a thickness that it does not require a support entirely around said arbor. This, however, would not always be the case, as it is often necessary to force arbors or mandrels into work of such a thickness that the support must entirely surround and fit said mandrel; otherwise said work would be bent or injured by the pressure applied thereto. For this purpose the plate 12 has been provided with a plurality of holes 19 extending laterally through said plate, each of which is of a different diameter, thus adapting said plate to substantially all sizes of arbors, said holes being arranged in such a manner about said plate that they may be severally brought into alinement with the plunger 7. It will, however, be observed that said holes 19 are arranged at a sufficient distance from the edge of the V-shaped slot 17 and the sides 20 of said plate in order that said plate will extend completely across and rest upon each said of the notch 6 in the work-support 5, whereby said plate will be supported simultaneously upon opposite sides of each of the holes 19.

It is essential that the plate 12 be permitted to move freely on said work-support 5 in substantially all transverse directions, that is, both transversely and longitudinally of said plate, in order that the holes 19 may be quickly moved into alinement with said plunger, and a handle 21 has been provided to facilitate the adjustment thereof.

55 In addition to the desirability of having the plate 12 move freely on the work-support 5 in substantially all transverse directions, it is also desirable that said plate should be at all times connected to the frame of the press 30 in such a manner that it will be in position for the operator to employ and will not be liable to become detached therefrom and lost. To accomplish this result an arm 22, preferably consisting of a rod, extends from the rear of the plate 12 through an opening

23 in the front wall of the frame 4 and into a recess 24 formed in said frame. A stud 25 is adapted to slidably engage said rod 22 and has a cylindrical stem 26 projecting upwardly therefrom and pivotally engaging the frame 4, permitting said plate to be moved on the work-support 5 substantially in all directions transversely thereof, but preventing the upward movement of said plate relatively to said work-support. 75

The movement of the plate 12 is sufficient to permit any one of the holes 19 and the slot 17 to be placed in alinement with the plunger 7, but beyond this said plate is prevented from being moved by the ends of the opening 23 against which said arm 22 is adapted to strike, while a screw 27 limits the outward longitudinal movement of the rod 22 relatively to the stud 25.

It will be seen that the holes 19 are arranged in two series 28 and 29 upon opposite sides of the V-shaped slot 17, each of said series being radially disposed relatively to the cylindrical portion 26 of the stud 25. Thus when the arm 22 is at the end 30 of the opening 23, as shown in dotted lines, the forward and rear movements of said plate will cause the holes in said series 28 to substantially aline with the plunger 7, providing said arm is kept in contact with said end of said slot, and should the plate 12 be moved transversely of said work-support until said arm 22 is at the end 31 of the opening 23, the series of holes 29 may likewise be successively alined with said plunger by the forward and rear movement of said plate. 90 100

In the operation of the device the plate 12 is adjusted or moved until a hole of the proper diameter or the portion of the slot 17, which corresponds to the diameter of the mandrel or arbor which is to be forced into or removed from the work, is brought into alinement with the plunger 7, after which the handle 21 is revolved to move said plunger down against the arbor to force the same through the work-supported by said plate, as illustrated in Fig. 1. 110

Having thus described my invention what I claim and desire by Letters Patent to secure is:

1. The combination, with an arbor press provided with a work-support, of a supplementary plate mounted to slide both longitudinally and transversely thereof on said work-support, said plate having a V-shaped slot adapted to receive arbors of various sizes, and means connecting said supplementary plate to said arbor press. 120

2. The combination, with an arbor press provided with a work-support, of a supplementary plate mounted on said work-support, said plate having a plurality of holes extending therethrough, a stud pivotally arranged on said press, and an arm attached 125 130

to said plate and slidably connected with said stud and adapted to permit both a longitudinal and a transverse movement of said plate relatively to said work-support.

5 3. The combination, with an arbor press provided with a work-support, of a supplementary plate mounted on said work-support, said plate having a plurality of holes extending therethrough, a stud pivotally arranged on said press, an arm attached to said plate and slidably connected with said stud and adapted to permit both a longitudinal and a transverse movement of said plate relatively to said work-support and 10 means to limit the extent of said transverse movement.

4. In an arbor press the combination of a plunger, means to reciprocate said plunger, a work-support, a supplementary plate provided with a plurality of holes extending therethrough, said supplementary plate mounted to slide both longitudinally and transversely thereof on said work-support, whereby said holes may be severally moved 20 into alinement with said plunger, and means to guide said plate to aline said holes respectively with said plunger.

5. In an arbor press the combination of a plunger, means to reciprocate said plunger, a work-support, a supplementary plate movable transversely and longitudinally thereof on said work-support and provided with a plurality of holes extending therethrough adapted to be severally moved into 25 alinement with said plunger, and means to limit the transverse movements of said plate relatively to said work-support.

6. In an arbor press the combination of a frame provided with a recess at the rear 40 thereof, a plunger, means to reciprocate said plunger, a work-support arranged substantially at right angles to the line of movement of said plunger, said frame having an opening at the rear of said work-support 45 and communicating with said recess, a stud pivotally arranged within said recess, a supplementary plate mounted on said work-support to move transversely thereof, said plate having a plurality of series of holes of various sizes extending therethrough parallel 50 with said plunger, and an arm extending from said plate through said opening and adapted to engage opposite ends of said opening and to slidably engage said stud, whereby said several series of holes may be positioned relatively to said plunger on said work-support.

7. The combination with an arbor press provided with a work-support and a plunger, of a supplementary plate mounted to

move transversely and longitudinally thereof on said work-support and provided with a plurality of holes of various sizes extending therethrough, said plate adapted to be moved on said work-support to severally 65 aline said holes with said plunger, said plate consisting of two layers of material, the upper layer of said material being substantially harder than the lower layer thereof. 70

8. In an arbor press the combination of a reciprocating plunger, a work-support, a supplementary plate provided with a plurality of series of holes extending therethrough, said plate being movable longitudinally and transversely thereof on said work-support, and means adapted to aline said several series of holes with said plunger and permit the holes constituting said series to be severally moved into alinement with said plunger. 75 80

9. The combination, with an arbor press provided with a work-support, of a supplementary plate mounted on said work-support and slideable transversely and longitudinally thereof on said work-support, said plate having a plurality of holes of different sizes extending therethrough. 85

10. The combination, with an arbor press provided with a work-support, of a supplementary plate mounted on and slideable transversely and longitudinally of said work-support in a plurality of directions, said plate having a V-shaped slot adapted to receive arbors of different sizes. 90 95

11. In an arbor press, the combination of a plunger, means to reciprocate said plunger, a work-support, a supplementary plate mounted on said work-support and slideable transversely and longitudinally thereof, said plate having a V-shaped slot adapted to receive arbors of various sizes. 100

12. The combination, with an arbor press provided with a work-support, of a supplementary plate mounted on said work-support, said plate having a V-shaped slot adapted to receive arbors of various sizes, a stud pivotally arranged on said press and an arm attached to said plate and slidably connected with said stud adapted to permit both a longitudinal and a transverse movement of said plate relatively to said work-support. 105 110

In testimony whereof I have hereunto set my hand in presence of two subscribing witnesses. 115
